UNITED STATES PATENT OFFICE

135,577

DESIGN FOR A PORTABLE HEATING UNIT

Harry B. Holthouse, Chicago, Ill., assignor to Galvin Manufacturing Corporation, Chicago, Ill., a corporation of Illinois

Application September 22, 1942, Serial No. 108,314

Term of patent 14 years

To all whom it may concern:

Be it known that I, Harry B. Holthouse, a citizen of the United States and residing at Chicago, in the county of Cook and State of Illinois, have invented a new, original, and ornamental Design for Portable Heating Unit, of which the following is a specification, reference being had to the accompanying drawings, forming part thereof, in which:

Fig. 1 is a perspective view of the top, front and one side of a portable heating unit showing my new design.

Fig. 2 is a top plan view thereof;

Fig. 3 is an elevational view of the one side shown in Fig. 1;

Fig. 4 is an elevational view of the other side thereof; and

Fig. 5 is an elevational view of the back thereof.

The characteristic features of my new design are shown in solid lines in the drawings.

I claim:

The ornamental design for a portable heating unit, substantially as shown and described.

HARRY B. HOLTHOUSE.
